UNITED STATES PATENT OFFICE.

WILLIAM J. DAVIS, OF CHARLOTTE, NORTH CAROLINA.

TRUNK-LOCK.

SPECIFICATION forming part of Letters Patent No. 499,971, dated June 20, 1893.

Application filed December 1, 1892. Serial No. 453,720½. (No model.)

To all whom it may concern:

Be it known that I, WILLIAM J. DAVIS, of Charlotte, in the county of Mecklenburg and State of North Carolina, have invented a new 5 and useful Improvement in Trunk and Valise Fastenings, of which the following is a full, clear, and exact description.

My invention relates to improvements in a class of trunk, box, or valise fastenings, in 10 which the main lock co-acts with other attachments, and effects a locking adjustment of the latter when the main lock is manipulated to lock it; and my invention consists in the peculiar construction and combination of 15 parts, as is hereinafter described and claimed.

Reference is to be had to the accompanying drawings, forming a part of this specification, in which similar letters of reference indicate corresponding parts in all the figures.

20 Figure 1 is a front perspective view of a trunk and the improved locking device thereon shown partly in dotted lines. Fig. 2 is an enlarged, broken and partly sectional view on the line 2—2 in Fig. 3, of the inner side of 25 the front wall portion of a trunk lid, a trunk body front wall broken and in part, and the improvement on said parts in full and dotted lines. Fig. 3 is a transverse section of parts 30 of the trunk lid and body and the improvement in a locked condition, on the line 3—3 in Fig. 2. Fig. 4 is a transverse sectional view 35 of parts on the same line as Fig. 3, the locking device being in unlocked condition. Fig. 5 is an enlarged and detached inner side view 40 of the hasp plate and its securing piece to which the hasp is pivoted, taken opposite the arrow 5, in Fig. 3; and Fig. 6 is a partial transverse section of the trunk body front wall, the closed lid front wall in part, and an improved supplementary locking device, on the line 6—6 in Fig. 2.

The lock proper for the trunk A, of which a represents the case, may be of any preferred form in a class having a horizontal slide bolt, 45 indicated at b, in Figs. 3 and 4, the other parts being omitted.

The lock case a, is secured with the interior mechanism, when the latter is in place therein, upon the front wall of the trunk body at 50 the longitudinal center, and near the top edge of the body; said case being located in a

proper shaped cavity formed in the side wall of the trunk.

The hasp piece c, is of the usual form, comprising an oblong plate of suitable dimensions, and by preference flanged along the edge on the inner surface, to stiffen the plate. 55 A bracket plate d, is provided, for an attachment of the hasp piece c, upon the front side of the trunk lid A'; two trunnions c', which 60 project oppositely from the sides of the hasp near its upper edge and which are located in recesses formed in projections c², on the bracket plate, serving to loosely connect the bracket plate and hasp piece. The bracket 65 plate d, is cut away of a suitable width and height from its lower edge, to allow the hasp-piece to vibrate between the projections c²; the thin keeper plate d', which covers the 70 recesses in which the trunnions c', are seated, being secured upon the inner surface of the hasp piece to adapt it to retain the trunnions in place and permit a free vibration of the hasp piece outwardly and upwardly.

A recess e, is cut in the front wall of the 75 trunk lid A' above the case a, for the reception of other features that are part of the improvement and which will presently be described. A rectangular base plate g, is furnished of sufficient area to cover the recess e, 80 and be secured by its overlapping edges to the side wall of the lid, the bracket plate d, being imposed upon the outer side of the base plate and thereto secured by any preferred means. Two similar flat L-shaped levers h, 85 are pivoted at their angular corners h' upon the inner surface of the base plate g, so that their main limbs will hang pendent and their lateral limbs overlap each other as indicated in Fig. 2. The lapped horizontal limbs of the 90 levers h, are each slotted from their free ends toward the pivots of the levers a proper length, for the reception of an arm i, that projects inwardly from the upper part of the hasp-piece c, through a vertical slot in the base 95 plate g, and also through the slots of the limbs, curving upwardly a sufficient degree to adopt the arm to rock the levers h, when the hasp piece is vibrated toward or from the lock case a.

100 On the inner face of the hasp-piece c, near its lower end, a shackle loop m, is secured

centrally, said loop having its body in a vertical plane, which will permit it to enter a slot m' , formed in the outer wall of the lock case a , and cross the path of the slide bolt b , in said case, so that the horizontal projection of the bolt will secure the hasp in the case and a reverse movement of said bolt release the hasp as is usual in this class of locks.

From the lower end of each of the levers h , 10 a slide bar n , is projected, which bars are extended toward the end walls of the trunk lid, and preferably are located in longitudinal grooves produced in the lower edge of the front wall of the lid, as represented in Fig. 2.

15 It will be seen, that the slide bars n , are each loosely connected to an end of the pendent limb of a lever h , that is farthest from the other end of the bar, so that the divergence of these pendent limbs of the levers h , 20 will draw the outer ends of the bars away from the end walls of the trunk lid, and an opposite movement of the pendent lever limbs that will cause their ends to approach each other, will project the free ends of the bars 25 toward these end walls of the lid, in an obvious manner.

The slide bars n are of such a proportionate length, as will adapt their outer ends to slide through two supplementary locking devices, 30 which are each formed of a socket piece o , and a tongue piece o' , which are secured in mating pairs at a proper distance from the main locking device before described.

As shown in Figs. 2 and 6, the tongue and 35 socket pieces are respectively secured upon the inner sides of the front wall of the trunk and the front wall of the lid, so that the slightly tapered tongue on the pieces o' , will freely enter the socket holes in the pieces o , 40 when the lid is closed, there being suitable recesses cut in the lid and trunk walls to allow the pieces o o' , to be embedded and secured therein with their inner faces flush with the inner faces of the parts to which they are secured.

45 The mating tongue and socket pieces o , o' , are in pairs transversely perforated, at such points as will cause the holes on all the pieces to lie in about the same horizontal plane, 50 when the lid is closed, thereby permitting the end portions of the slide bars n , that are nearest to these pairs, to slide through the aligned holes when the hasp piece c , is vibrated toward the lock case a , which will secure the 55 mating socket and tongue pieces o , o' , together

in pairs. When the lock a and hasp piece c are fastened together by a proper key, that is adapted to slide the bolt b , and work other parts of the main lock so as to retain this bolt in locked adjustment, said lock, together with 60 the slide bars and interlocked tongue and socket pieces o , o' , will firmly lock the lid A' , on the trunk body A , at three different points, thus dispensing with other appliances that are usually provided to latch the trunk 65 lid fast to the body of the trunk, and release the main lock from strains incurred through rough handling of the trunk.

It will be evident that by a proper proportion of parts, the improvement may be applied to secure the hinged and folding portions of a valise together, locking them at three points, and requiring the main lock to be unlocked and hasp pieces vibrated therefrom to release the supplementary locks that 75 are near the ends of the receptacle.

Having thus described my invention, what I claim as new, and desire to secure by Letters Patent, is—

1. The combination with a receptacle, a hinged lid therefor, a hasp vibratable on a base plate on the lid, and a main lock on the receptacle, of L-shaped levers pivoted at their angles on the base plate, and adapted to loosely engage an arm on the hasp, slideable 85 bars pivoted to pendent limbs of the levers, and socket and tongue devices adapted to receive the ends of the bars in aligning holes and be locked thereby, substantially as described. 90

2. The combination with a trunk body, a lid therefor, a main lock on the trunk body, a hasp on the lid adapted to vibrate on a bracket plate, a base plate whereon a bracket plate is secured, and an arm inwardly projected through a slot in the base plate, of two L-shaped levers pivoted by a corner of each and slotted in overlapping limbs to receive said arm, two slide bars pivoted to the lower ends of pendent limbs on the levers, and two pairs 100 of tongue and socket pieces secured on the lid and body and transversely perforated in alignment to receive the ends of the slide bars which are projected when the hasp is folded toward the main lock, substantially as described. 105
